UNITED STATES PATENT OFFICE.

MARY R. MAX, OF PITTSBURGH, PENNSYLVANIA.

HEATING DEVICE.

Application filed July 19, 1924. Serial No. 727,029.

To all whom it may concern:

Be it known that I, MARY R. MAX, a citizen of the United States, and a resident of Pittsburgh, in the county of Allegheny, 5 Pennsylvania, have invented certain new and useful Improvements in Heating Devices, of which the following is a specification.

This invention relates to heating devices 10 and more particularly to heating devices to be used for maintaining a liquid or other fluid at a constant temperature, as for example when used for medical treatment.

In such processes as enteroclysis and protoclysis, it is essential to maintain the solution or liquid that is being fed into the human body at a constant temperature, and such maintenance at a uniform temperature is absolutely essential if proper results of 20 such treatment are to be obtained. But in the prior art processes there have been no devices which enabled the accomplishment of this result without much care and difficulty. For example in the Murphy drip treatment, the liquid after being heated to the desired temperature was maintained at this temperature during the drip feeding, by surrounding the same with hot water bottles, etc. Obviously such an apparatus is 30 cumbersome and requires constant and careful manipulation.

One of the objects of the present invention is to supply an apparatus which is simple in construction and yet will give positive control without requiring constant watching.

Other and further objects and advantages of this invention will appear from the more detailed description set forth below, and 40 particularly in connection with the drawing wherein there is set forth by way of example, and not by way of limitation, one form that the device may take and which is the preferred form to be used. The drawing shows in Figure 1 a plan view of the device; in Figure 2 an end view of the device; and in Figure 3 the complete structure assembled and ready for use. And while a specific embodiment of the device 45 will be described as shown in the drawing, it will be understood that various changes therein may be made by those skilled in the art to which this invention appertains, without departing from the spirit or scope of this invention.

The preferred form as shown in the draw-

ing sets forth a tube A preferably of glass through which the liquid to be heated flows from a source of such material such as the receptacle or container 1, to which it is connected by suitable tubing, also preferably of glass. This tube A is surrounded by a porcelain tube B which serves to protect the tube A. A third tube C of insulating material which may be made of insulating material of any desired kind, is placed about the tube B, and acts as a cover for the resistance wire coil D, preferably of nichrome wire which is placed about the tube B. The coil of wire D is supplied with the conventional plug attachment E so that it may be attached to any desired source of current, preferably 110 volt which allows of its use very widely. The other end of the tube A is connected by the usual glass and rubber 75 connections to the rectal tube or other desired connection.

In use the device is arranged so that the liquid from the container will flow through the glass tube A at the desired rate, for example from 40 to 60 drops per minute. Having determined the rate of flow, the current is then turned on, and the arrangement is such that the liquid in passing through the tube A will be heated to a uniform temperature, in the preferred case of 105° F. although this temperature may vary if desired depending upon the heating surface used, and even in the case of use in protoclysis may vary from 103 to 108° F. 90 for example. When the current is on the temperature of the solution cannot exceed 108° F. when given at 40 drops per minute, and it does not exceed 105° F. when given at 60 drops per minute. In the preferred case a very high resistance wire is used, there being about 100 feet of enamel coated wire making about 400 turns about the porcelain tube. The guage of the wire is preferably 26. 100

The device illustrated is particularly valuable in enteroclysis wherein a solution is given to the rectum to be absorbed by the bowel for medicinal purposes, by a drip process. In such use the device heats the solution to approximately 105° F. after the rate of flow has been properly regulated so that the solution will reach the bowel at the proper temperature, and will readily maintain the solution at that temperature. 105

Valves or stopcocks or other similar devices may obviously be used with the appa-

ratus either in the connection between the heating tube and the container, or between the heating tube and the delivering tube, or at both places, to control the rate of flow of 5 the solution through the apparatus.

Having thus set forth my invention, I claim:

10 A heating device for liquids used in en-
teroclysis and protoclysis which consists of
an inner glass tube for receiving the liquid
to be heated, a porcelain tube surrounding
the said glass tube to protect the same, a
ribbon conductor wound on the said por-

celain tube, and an insulating cover about
said coil of wire, and means for attaching 15
the coil of wire to a source of electric cur-
rent, a valve for feeding the liquid to be
heated to the glass tube at the rate of from
40 to 60 drops per minute, the relation be-
tween the heating and conducting surfaces 20
of the device being such that the temper-
ature of the liquid passing through the ap-
paratus at the rate set forth will not vary
from the limits of 103° to 108° F.

MARY R. MAX.
